UNITED STATES PATENT OFFICE.

SAMUEL C. HILL, JOHN M. GIBSON, AND JOHN E. WRIGHT, OF WHEELING, WEST VIRGINIA.

SIPHON-ACTION WATER CLOSET.

Application filed April 27, 1923. Serial No. 635,131.

To all whom it may concern:

Be it known that we, SAMUEL C. HILL, JOHN M. GIBSON, and JOHN E. WRIGHT, citizens of the United States of America, and residents of Wheeling, county of Ohio, and State of West Virginia, have invented certain new and useful Improvements in Siphon-Action Water Closets, of which the following is a specification.

10 This invention relates to siphon action water closets, and it has for its primary object the provision of a closet of this character which may be cast in a minimum number of parts and which, consequently requires a minimum number of joining or "sticking" operations.

15 A further object is to provide a method of forming siphon action closets in which the production of the tortuous closet passageways is effected without the difficulties ordinarily encountered in or attendant upon the manufacture of such closets by preexisting methods.

20 A still further object is to simplify closet forming methods to the extent that there is effected a substantial reduction in the amount of labor involved, and to provide a method which may be carried out without the requirement for a high degree of expert 25 knowledge of the art and without the exercise of more than ordinary dexterity or skillfulness on the part of the artisan.

25 Another object within the contemplation of the invention is the production of a closet bowl having an improved construction of flushing rim.

30 With these and other objects in view, the invention resides in the features of construction and in the process of manufacture 35 which will hereinafter be fully described, reference being had to the accompanying drawings, in which—

40 Figure 1 is a vertical longitudinal section of a siphon action closet produced in accordance with the invention;

Figure 2 is a transverse section of the same;

45 Figure 3 is a perspective view of the base and one of the mold sections employed for casting one side of the body portion and 50 the base of the closet;

Figure 4 is a similar view of the other mold section so employed;

55 Figure 5 is a similar view of the plug employed in shaping the outlet or waste passage;

Figure 6 is a cross section of the mold sections shown in Figs. 3 and 4 disposed in complementary relation and showing a cross section of the body formed thereby, said section being taken substantially on lines 60 6—6, Figs. 3 and 4;

Figures 7 and 8 are perspective views of the opposing mold sections employed in casting the opposite side of the closet body;

Figure 9 is a cross section of said sections 65 in assembled relation;

Figure 10 is a perspective view of the base section of the bowl forming mold;

Figure 11 is a perspective view of the under side of the top section of said mold; 70

Figure 12 is a cross section of said bowl forming mold sections in assembled relation;

Figures 13 and 14 are inner face perspective views of the mold sections employed for forming the upper part of the flushing rim; 75

Figure 15 is a transverse section of said sections in assembled relation;

Figure 16 is a rear end elevation of the same;

Figure 17 is an enlarged section of a fragmentary portion of the bowl, illustrating the rim structure; and—

Figure 18 is a similar section taken through the rear end of said bowl.

Referring to said drawings, A indicates generally the siphon action closet which is composed of a body portion 1, a base 2 having therein a waste passage or drain vent 3, a bowl 4, a trap 5 separating the usual ascending and descending legs 6 and 7 of a 90 siphon passageway leading from the interior of the bowl 4 to the waste passage 3, and a hollow rim 8.

The bowl 4 and the lower part or half 8^a of the rim 8 are cast integrally, as is shown 95 in Figs. 12, 17 and 18, and the upper part or half 8^b of said rim, cast separately, as shown in Figs. 15 and 16, is bonded to said lower half 8^a through the intermediacy of a heavy slip, introduced in the usual manner, 100 for producing a hollow flushing rim which is to all intents an integral structure.

The upper interior surface of the bowl 4 has a fluted formation, ribs 9 alternating with grooves or channels being formed on said bowl. Said ribs and said channels extend inward horizontally from the interior vertical face of the inner upright wall of the trough-like lower half 8^a of the rim, and thence extend downwardly along the inte- 110

rior of the bowl 4, as shown, said ribs being gradually reduced in depth until they wholly disappear at a suitable level below said rim. The inner flat portion of the under face of the upper half 8^b of the rim rests directly upon the horizontal tops of said ribs 9. An internal downwardly extending lip 8^c formed on the upper half 8^b of the rim seats closely against the upper inwardly facing portions of said ribs 9 and constitutes a deflector by which flushing water passing from the interior of the rim through the passages intermediate said horizontal portions of the ribs is deflected downward.

It will be particularly noted that, due to the fact that the ribs 9 and the intermediate channels are formed in molding the bowl, the same are accurately and regularly formed and spaced, thus providing for directing the flushing water in the form of numerous jets so that every part of the interior surface of the bowl is flushed, thereby overcoming the faults due to imperfect and improperly positioned perforations frequently encountered in closet bowls in which the inner under sides of the rims are perforated manually, as ordinarily, following the molding operation.

Another objection to the formation of perforations by hand punching is that the material punched out may remain within the hollow of the rim in a position or positions seriously interfering with the flow of the water. This objection is of course wholly obviated in the present invention, and, furthermore, since the rim is cast in two parts, as aforesaid, the walls of the latter may be made of uniform thickness throughout, thus avoiding internal obstructions which might result in retarding or otherwise interfering with the flow of the water.

In constructing the closet, the bowl 4 and the body 1 are molded separately, following which said parts are assembled or joined to form a practically unitary structure, as will hereinafter be described. Additionally, said body 1, together with the base 2 and the trap 5, is molded in two separate parts which are subsequently joined in the formation of the body.

Referring, first, to the body 1 and the method of forming the same, a three-part mold is employed for molding integrally the base 2, one side or half of the trap 5 and one side of the body, and a two part mold is employed for molding the other half of the trap and the opposite side of the body.

Forming one part of the aforesaid three-part mold is a base B illustrated in Figs. 3 and 6, which is preferably of oblong oval form and which has a flat marginal seating rim or ledge 10 for the reception of the lower edge portions of a pair of complementary side members 11 and 12. Defining

the inner edge of said marginal ledge is the outer edge 13^a of a table 13 having its level elevated slightly above that of said ledge; and spaced inward slightly from the said edge of the table 13 at one end of the latter is an elevated panel 14. Similarly spaced and elevated above said table at the opposite end of the latter is a relatively smaller panel 15, herein shown as of crescent shape; and interposed between said panels and spaced from the latter to form channels 16 is a ring 17, said ring enclosing the upper end of an opening 18 which extends through the base B and which is adapted to receive therein a plug 19, shown in Fig. 5. As will be apparent, the seated lower edge portions of the side members 11 and 12 and the elevated table 13, panels 14 and 15, ring 17 and plug 19 are so associated relatively that they are adapted to shape the hollowed under side of the closet base 2, forming therein the drain vent or passage 3 and forming thereon the encircling ring-like flange 20 and the outer supporting flange 21.

The side members 11 and 12 of said three-part mold are designed to be supported by the mold base B in opposing complementary relation and, in conjunction with said base B, to form therebetween a wholly enclosed molding space for a side 1^a of the closet body 1 and for a laterally disposed wing 5^a, the latter constituting one complementary part or half of the trap 5. The opposite internal molding spaces provided in said side members are shaped to impart to the body wall or side 1^a the desired contour or configuration and the required thickness. The member 12 has formed therein a recess or molding space 22 of the irregular form or design required in the production of the wing 5, and having a depth approximating one half that of the trap 5. A filler opening or hole 23 of suitable size and form is provided in the mold base B, as shown.

Instead of the body forming mold being made in three parts, as described, the base and one of the sides, as the side 11, may be made integral, as shown in Fig. 6.

The two-part mold employed in the formation of the opposite side 1^b of the closet body and the opposite half or wing 5^b of the trap is composed of opposite side members 24 and 25 having their confronting internal faces shaped to give to the body wall 1^b the desired contour or configuration and thickness. The member 24 is flanged at the lower part of its inner portion to provide a seating ledge 26 upon which the member 25 rests. Said member 24 has formed in its inner face a recess or molding space 27 which corresponds in all substantial respects to the recess 22 of the member 12 of the three-part mold hereinbefore described, said recess 27 being adapted for shaping the wing 5^b which, in the finished body, is joined to the

wing 5^a, complementing the latter in the formation of the trap 5. One or more filler openings 40 are provided at suitable points, as shown.

- 5 It will be noted that the opposite sides of the closet body formed as described have their upper edges located in approximately the plane of the uppermost part of the ascending leg of the siphon passageway.
- 10 In the formation of the bowl 4 a two-part mold is employed, the same consisting of a lower, or base, member 28 and an upper, or top, member 29. Said base member 28 has a hollow bowl shape with its interior corresponding in contour with that desired for the exterior of the bowl 4, whereas the top member 29 comprises an upwardly removable core 29^a of the approximately inverted-cone shape required for shaping the internal surfaces of the bowl walls.

The member 28 has an annular flange 28^a surrounding its upper edge designed to receive thereon in seated relation a corresponding flange 29^b formed on and surrounding the upper part of the core 29^a. An internal rabbet-like ledge 30 formed in the upper part of the walls of the base member 28, and a downwardly facing rib 31 formed on the flange 29^b of the top member 29 are adapted to conjointly give shape to the lower half 8^a of the flushing rim 8, said rib forming the channel which, in the finished article, constitutes the lower part of the water passage in said rim.

25 The core 29^a has formed around its exterior beneath its flange 29^b a succession of regularly spaced alternate channels or flutes 32 and ribs or fillets 33 designed to form the ribs 9 and intermediate channels of the closet bowl 4, the flutes 33 being adapted to have the horizontal upper ends thereof partially overhanging the ledge 30 of the base member 28.

The base member 28 has a channel 34 crossing the flange 29^a at its rearmost part for shaping the under side of the usual tubular supply connection 35 of the closet; and formed in the wall of the base member is a relatively deep vertically disposed channel 37 which terminates at its lower end in a socket-like seat 38. The core 29^a has an external rib-like swell 29^c formed thereon which corresponds in general outline to and which cooperates with said channel for shaping the bowl 4 to form interiorly of the latter a vertical concave channel constituting a water course or fan wash 39 through which a large proportion of the volume of flushing water entering through the supply connection 35 is conducted directly down along the rear wall of the bowl to the funnel-like lower bottom outlet of said bowl.

The upper part 8^a of the rim 8 is formed by two complementary mold sections 41 and 42 which have their confronting faces shaped

to give said part the required configuration, as shown in Figs. 13, 14, 15 and 16.

The various mold parts herein described are preferably made of plaster of Paris or other material suitable for absorbing the requisite proportion of the moisture of the ceramic materials employed.

In assembling, the two cast sections of the body portion 1 are placed in complementary relation and the bowl 4 is superposed thereon, following which the upper part 8^b of the rim is mounted in place, the necessary amount of slip for uniting the abutting edges of the various parts being introduced in the manner well understood by those skilled in the art. The parts so assembled are then allowed to dry and are subsequently baked to completely unite the whole in a structure which, practically considered, is integral throughout.

Among the various advantages possessed by the method of casting hereinbefore described is that each of the various parts is accurately formed of a predetermined shape, proportions and dimensions and that the surfaces are insured the desired regularity of contour.

What is claimed is—

1. The method of constructing siphon action closets, which comprises separately forming the opposite sides of the closet body, each with an integral wing portion, said wings constituting complementary portions of the trap, uniting said sides and said wings, separately forming the closet bowl, and uniting said bowl to said body.

2. The method of constructing siphon action closets, which comprises forming the closet base and one side of the body as a unitary structure, separately forming the opposite side of said body, each of said sides having an integral laterally directed wing, uniting the last mentioned side to the base and to the first mentioned side and uniting said wings to form the trap, separately forming the closet bowl, and uniting said bowl to said body.

3. The method of constructing siphon action closets, which comprises molding the opposite sides of the closet body in two separate complementary parts, each having an integral laterally extending wing, said wings constituting complementary portions of the trap, uniting said sides and said wings in complementary relation, separately forming the closet bowl, seating said bowl in superposed relation to said body, and uniting the engaging surfaces of said bowl and said body.

4. The method of constructing siphon action closets, which comprises forming the closet base and one side of the body as a unitary structure, separately forming the opposite side of said body, each of said sides having an integral laterally directed wing,

uniting the last mentioned side to the base and to the first mentioned side and uniting said wings to form the trap, separately forming the closet bowl together with the lower part of the flushing rim and with spaced ribs on the latter extending down the interior face of the bowl, uniting said bowl to said body, separately forming the top of the rim with an inner deflecting lip, mounting said rim top upon said lower rim part with said deflecting lip seated against the inwardly facing surfaces of said ribs, and uniting the engaging surfaces of said rim parts one to the other.

15 5. The method of constructing siphon action closets, which comprises including the opposite sides of the closet body in two separate complementary parts, each having an integral laterally extending wing, said 20 wings constituting complementary portions of the trap, uniting said sides and said wings in complementary relation, separately forming the closet bowl together with a trough-like lower part of the flushing rim and with 25 flutings in the inner edge portion of said rim part and in the upper interior surface of said bowl, uniting said bowl to said body, separately forming the top part of the rim with an inner downwardly extending lip, 30 and uniting said top part of the rim to said lower part with said lip resting upon the inwardly facing surfaces of the fillets which 35 separate the flutes.

35 6. The method of constructing siphon action closets, which comprises separately forming the opposite sides of the closet body with their upper edges located in the plane of the ascending leg of the siphon passageway, each side formed with an integral 40 wing, said wings constituting complementary portions of the trap separating said leg from the descending leg of said passageway, uniting said sides and said wings, separately forming the closet bowl, and uniting said 45 bowl to said upper edges of the sides of the body.

7. A siphon action closet comprising a base having a waste passage therein, a body having therein trap-separated ascending 50 and descending legs of a siphon passageway, said base, one side of said body and a portion of said trap being formed integrally, and the opposite side of said body and an integral complementary portion of said trap 55 being formed separate from and united in complementary relation to the first mentioned integral structure, and a separately molded bowl superposed upon and united to said body along the upper edge of the latter.

60 8. A siphon action closet comprising a base having a waste passage therein, a body having therein trap-separated ascending and descending legs of a siphon passageway, said base, one side of said body and a portion

of said trap being formed integrally, and 65 the opposite side of said body and an integral complementary portion of said trap being formed separate from and united in complementary relation to the first mentioned integral structure, and a separately molded 70 bowl superposed upon and united to said body along the upper edge of the latter, said bowl having a flushing rim and having flutes formed therein beneath the inner edge of said rim.

75 9. A siphon action closet comprising a base having a waste passage therein, a body having therein trap-separated ascending and descending legs of a siphon passageway, 80 said base, one side of said body and a portion of said trap being formed integrally, and the opposite side of said body and an integral complementary portion of said trap being formed separate from and united in complementary relation to the first mentioned integral structure, and a separately molded 85 bowl superposed upon and united to said body along the upper edge of the latter, said bowl having a flushing rim composed of complementary lower and top portions, 90 said lower portion being of trough shape and formed integral with said bowl, the inner upright wall of said lower portion having radial channels therein separated by rib-like fillets which extend thence downward along the inner surface of the bowl, the top portion of said rim being formed separately and having an inner downwardly extending lip, said top portion being united 95 to said lower portion in seated relation to the fillets of the latter and with its said lip resting upon the faces of those portions of the fillets which extend downward within the bowl.

100 10. In a siphon action closet, a bowl having a flushing rim, the lower portion of said rim being of trough shape and formed integral with said bowl, the inner upright wall of said lower portion having spaced flute-like channels therein alternated with 105 rib-like fillets which are prolonged and extend downward over the upper interior surface of said bowl, the upper portion of the rim being seated upon said lower portion with a portion of its under face resting upon the top portion of said fillets, said upper portion having an inner depending lip which rests against the faces of those portions of the fillets which extend downward within the bowl.

110 In testimony whereof we affix our signatures in presence of two witnesses.
